(57) **CLAIM**

The ornamental design for a visual aid transducer protector, as shown and described.

DESCRIPTION

FIG. 1 is a top perspective view of our visual aid transducer protector design;

FIG. 2 is a left side view of the visual aid transducer protector shown in FIG. 1;

FIG. 3 is a front view of the visual aid transducer protector shown in FIG. 1;

FIG. 4 is a right side view of the visual aid transducer protector shown in FIG. 1;

FIG. 5 is a back view of the visual aid transducer protector shown in FIG. 1;

FIG. 6 is a top view of the visual aid transducer protector shown in FIG. 1;

FIG. 7 is a bottom view of the visual aid transducer protector shown in FIG. 1; and,

FIG. 8 is a bottom perspective view of the visual aid transducer protector shown in FIG. 1.
